UNITED STATES PATENT OFFICE.

CHARLES W. MUELLER, OF ST. LOUIS, MISSOURI, ASSIGNOR TO LEWIS INVISIBLE STITCH MACHINE CO., OF ST. LOUIS, MISSOURI, A CORPORATION OF MAINE.

METHOD OF SEAMING COATS AND THE LIKE.

Application filed February 9, 1924. Serial No. 691,637.

This invention relates to new and useful improvements in methods for seaming sewed articles generally, although the invention is more particularly directed to a method of joining the edge portions of the fore-part, facing and interlining of a coat.

Heretofore, the practice has been to first arrange the fore-part and the facing of a coat in a superimposed relation with their outer edges coinciding, placing a tape upon the fore-part adjacent said outer edges, and stitching the entirety by a single line of through-and-through stitches. An interlining is then stitched to the tape, generally by a line of blind stitches, and the facing is then turned over upon the interlining. Although the fold is subsequently pressed, there is a tendency during the wearing of the coat for the edge thus seamed and folded to roll, that is, the edge portion of the facing tends to roll outwardly. To overcome this objection it has been customary to hand stitch the facing to the interlining, but this hand operation is necessarily slow and consequently costly, the stitches are spaced irregularly and great care must be exercised in order to avoid any of these hand made stitches from penetrating the fore-part of the coat, or from passing entirely through the facing and thereby becoming visible on the "fair" side thereof, or creating puckering in the outer face or "fair" side of the facing due to the stitches being set too tightly.

My invention has amongst its several objects, to provide a method of seaming the edges of coats which will result in a greater production at a lesser cost, in insuring a sufficiently tight seam to prevent rolling of the edge, in avoiding any of the stitches being visible on the "fair" side of the facing, and in avoiding any puckering effect on the "fair" side of the facing.

In the accompanying drawings which illustrate the successive steps in carrying out my method, the parts are considerably exaggerated and the parts are spread out to better disclose the construction. In the drawings:

Figure 1 illustrates the first step in my method, and shows in section, the facing, fore-part, and tape arranged in superposed

relation and seamed by a line of through-and-through stitches.

Figure 2 illustrates the second step in my method, and is similar to Figure 1, except that it shows the joining of the interlining to the tape by a line of blind-stitches.

Figure 3 illustrates the third step in my method the view being in section and showing the parts folded and temporarily seamed.

Figure 4 illustrates the fourth step in my method, the view being in section and more or less diagrammatic, and showing the folded position of the work and the relation of the stitches which join the facing and interlining.

Figure 5 is a view similar to Figure 4, but showing the work being fed through a blind-stitch sewing machine.

Figure 6 illustrates the fifth step in my method, and is a view similar to Figure 4 but showing the lining only being penetrated by a line of blind-stitches.

Figure 7 is a view similar to Figure 6 but showing the work being fed through the sewing-machine.

Figure 8 is a sectional view of the completed seam, the stitches being diagrammatically shown, and

Figure 9 is a plan view of the seam showing the line of stitches which successively engage the facing and the lining and the lining only.

Like reference numerals designate corresponding parts throughout the several figures of the drawings.

In carrying out my method, I first construct a primary seam for the edge of a coat by disposing the facing 5 and the forepart 6 in superposed relation with their outer or marginal edges 7 coinciding. A tape 8 is positioned upon the fore-part adjacent said outer edges 7 and the three parts are then fed through a single needle sewing machine 9 so as to initially seam said parts by a line of through-and-through stitches 9 which parallel said edges 7, as shown in Figure 1.

The work is then passed through a blind stitch sewing machine and an interlining 10 is attached to the tape 8 by a line of blind stitches which is diagrammatically illustrated at 11 as shown in Fig. 2.

The purpose of securing the interlining to

the primary seam is an incident of manufacture, and, therefore, the interlining and the tape may be considered as an entirety, viz., an interlining which is secured to the fore-part and facing by the line of stitches 9.

I then fold the facing 5 upon the interlining 10 and temporarily seam the parts as thus folded by a line of basting stitches 12, which are preferably of the single thread 10 chain stitch type and are disposed in a line parallel to and adjacent the infolded edges 7 of the facing and fore-part, as shown in Fig. 3. The edge portion thus folded and temporarily stitched, will hereinafter be referred to as the main seamed portion 13.

I then open the work thus previously seamed, so as to position the facing 5 in a substantially horizontal plane on one side of the main seamed portion 13 and position 20 the interlining 10 and fore-part 6 in superposed relation and in the same horizontal plane as the facing, but on the other side of the main seamed portion 13, said main seamed portion 13 being disposed below the 25 horizontal plane containing the facing, fore-part and lining and arranged with its marginal edges 7 projecting upwardly. Thus the facing and the interlining are folded in one direction and the fore-part is folded in 30 the opposite direction, along a line parallel to the main or previously formed seam. By means of the basting stitches 12, the facing 5 and interlining 10 are retained in fixed relation directly above the main seamed portion 35 13.

In this position of the work, it is fed through a blind-stitch sewing machine, such as constitutes the subject-matter of my copending application filed February 9, 1924, 40 Ser. No. 691,638. This machine seams the facing and interlining by a line 14 of blind stitches, the seam constituting the subject-matter of my copending application filed January 9, 1924, Ser. No. 685,174.

45 The sewing machine includes a needle 15 having a needle thread 16 and a cooperating rotary hook 17 carrying a bobbin thread 18, the needle and the hook being both disposed above the work and the needle arranged to 50 oscillate about a horizontal axis and across the line of seam. Cooperating with the work, is a presser-foot 19 having an opening 20, a work clamp 21, a feed dog 22, and a plunger 23. The plunger reciprocates vertically in timed relation to the needle and feed, and comprises relatively fixed and movable parts 24 and 25, respectively, forming therebetween a guiding channel 26 for the main seamed portion 13. The plunger engages the under face of the work and causes 55 the latter to be formed into a node which is projected by said plunger through the presser-foot opening 20 into the path of the needle 15. In alternate reciprocations of the plunger, the relatively fixed part 24 is pro-

jected above the relatively movable part 25, and inasmuch as the fixed part 24 engages the facing, the latter will be elevated into the same horizontal plane as the interlining which interlining and fore-part are disposed above and are engaged by the relatively movable part 25 of the plunger. In this position, as shown in Fig. 5, the needle 15 will enter and emerge from the upper faces of the facing 5 and interlining 10, and leave a needle thread loop 27, which is anchored by the bobbin thread 18. In the intermediate reciprocations of the plunger, the relatively stationary part 24 will remain in its normal position, i. e., with its upper end disposed in substantially the same horizontal plane as the upper end of the relatively movable part 25. In this position as shown in Figure 7, the needle 15 will not enter the facing 5 but will enter and emerge only from the upper face of the interlining 10 by reason of the facing 5 being disposed in a plane below the path of reciprocation of the needle 15, and leave a needle thread loop 28 in said interlining, the loop 28 being anchored by the bobbin thread 18. The sewing machine referred to above, is provided with an intermittent tension mechanism which acts on the needle thread 16 to loosely concatenate the needle thread loops 27 with the bobbin thread 18 and to tightly concatenate the needle thread loops 28 with said bobbin thread. Thus the stitches which engage the facing and interlining are loosely set whereas those stitches which engage the interlining only are tightly set.

After the work has been removed from the blind stitch sewing machine, it is pressed and the line of basting stitches 12 is withdrawn.

If the usual needle thread tension were employed, and this tension were loosened, then all of the stitches would be loosely set and a seam of such looseness would be created which would fail to function to retain the seam from rolling, although such loosely set stitches would eliminate a puckered appearance of the outer face or "fair" side of the facing.

By reason of the needle thread loops penetrating the facing and interlining during every other stitch only, coupled with the loose setting of such stitches, and with the tight setting of the alternate stitches which engage the interlining only, an ideal situation results in that the facing is retained against rolling during the wearing of the garment and the appearance of dimples or puckering on the outer face or "fair" side of the facing is prevented.

From the foregoing it will be seen that my method includes the joining of two previously seamed body fabrics, namely the facing and the interlining, thence folding the fabrics outwardly along a line parallel to

said previously formed seam whereby said fabrics will lie in a substantially horizontal plane on opposite sides of said seam, and thence feeding said fabrics past a stitch forming mechanism and simultaneously joining said fabrics adjacent said fold by a line of blind stitches including a series of equally spaced penetrant needle thread loops which enter and emerge respectively from the upper faces of the fabrics.

I claim:—

1. The method of joining two fabrics consisting in first seaming the fabric sections in superposed relation by a line of through-and-through stitches adjacent to and parallel to one edge thereof, then folding the fabric sections outwardly on opposite sides of said seam and disposing the seamed edge portion below the horizontal plane containing the sections, and finally joining said fabric sections by a line of stitches directly above said seamed portion while said fabric sections are disposed in said horizontal plane.

2. The method of joining two previously seamed superimposed body fabrics consisting in folding the fabrics outwardly along a line parallel to said previously formed seam whereby said body fabrics will lie in a substantially horizontal plane on opposite sides of said seam, and thence intermittently feeding said fabrics past a stitch forming mechanism and simultaneously joining said fabrics adjacent said fold by a line of blind stitches including a series of equally spaced and anchored penetrant needle thread loops which alternately enter the upper face of one only of the body fabrics, and enter and emerge respectively from the upper faces of both body fabrics.

3. The method of joining two body fabrics consisting in first arranging said body fabrics in superposed relation with their outer edges coinciding, then initially seaming said fabrics by a line of through-and-through stitches extending parallel to said outer edges, then folding the lower fabric onto the upper fabric so as to dispose the seamed portion therebetween, then securing said fabrics by a line of basting stitches extending parallel to said fold, and forming a resultant main seamed portion, then folding the fabrics outwardly so as to dispose them in a substantially horizontal plane on opposite sides of said main seamed portion, and finally joining said fabrics adjacent said fold by a line of blind stitches including a series of equally spaced and anchored penetrant needle thread loops which enter and emerge from the upper faces of the body fabrics.

4. The method of joining two body fabrics consisting in first arranging said body fabrics in superposed relation with their outer edges coinciding, then initially seam-

ing said fabrics by a line of through-and-through stitches extending parallel to said outer edges, then folding the lower fabric onto the upper fabric so as to dispose the seamed portion therebetween, then securing 70 said fabrics by a line of basting stitches extending parallel to said fold, and forming a resultant main seamed portion, then folding the fabrics outwardly so as to dispose them in a substantially horizontal plane on opposite sides of said main seamed portion, and thence intermittently feeding said fabrics past a stitch forming mechanism and simultaneously joining said fabrics adjacent 80 said fold by a line of blind stitches including a series of equally spaced and anchored penetrant needle thread loops which alternately enter the upper face of one of the body fabrics, and enter and emerge respectively from the upper faces of both 85 body fabrics, said stitches being alternately set tight and loose.

5. The method of seaming coats consisting in first securing the facing, fore-part and interlining in superposed relation by a line of through-and-through stitches adjacent to and parallel to one edge thereof, then folding the facing so as to dispose the same in a substantially horizontal plane containing the fore-part and interlining and positioning the seamed edge portion below said horizontal plane, and finally joining said facing and interlining by a line of stitches directly above said seamed portion while said facing and interlining are disposed in 100 said horizontal plane.

6. The method of seaming coats consisting in first securing the facing, fore-part and interlining in superposed relation by a line of through-and-through stitches adjacent to and parallel to one edge thereof, then folding the facing over and upon the interlining, then securing the fabrics by a line of basting stitches extending parallel to said fold and forming a resultant main seamed portion, then folding the facing outwardly so as to dispose the same in a horizontal plane containing the fore-part and interlining, and finally joining said facing and interlining directly above the main seamed portion by a line of blind stitches including a series of equally spaced and anchored penetrant needle thread loops which enter and emerge from the upper faces of said facing and interlining.

7. The method of seaming coats consisting in first securing the facing, fore-part and interlining in superposed relation by a line of through-and-through stitches adjacent to and parallel to one edge thereof, then folding the facing over and upon the interlining, then securing the fabrics by a line of basting stitches extending parallel to said fold and forming a resultant main seamed portion, then folding the facing outwardly so as 130

to dispose the same in a horizontal plane containing the fore-part and interlining, and finally joining said facing and interlining directly above the main seamed portion by a line of blind stitches including a series of equally spaced and anchored penetrant needle thread loops which enter and emerge from the upper faces of said facing and interlining, said stitches being alternately set tight and loose. 10

In testimony whereof I hereunto affix my signature.

CHARLES W. MUELLER.
